UNITED STATES PATENT OFFICE.

ELIHU THOMSON, OF LYNN, MASSACHUSETTS, ASSIGNOR TO GENERAL ELECTRIC COMPANY, A CORPORATION OF NEW YORK.

ARC-LAMP-FEEDING MECHANISM.

Application filed July 25, 1923. Serial No. 653,801.

To all whom it may concern:

Be it known that I, ELIHU THOMSON, a citizen of the United States, residing at Lynn, in the county of Essex, State of Massachusetts, have invented certain new and useful Improvements in Arc-Lamp-Feeding Mechanisms of which the following is a specification.

My invention relates to feeding mechanisms for arc lamps. More particularly it relates to feeding mechanisms of the type which are operated by an electric motor through the medium of suitable gears. Heretofore arc lamps have been made with a constant feed arrangement which is operated by gearing up the electrode holders and an electric motor through the medium of suitable mechanism. This gearing mechanism is so designed as to feed the electrodes toward or away from each other at a predetermined rate, determined by the rate of consumption of a standard electrode. However, electrodes do not all run the same. Electrodes from one batch may be consumed faster or slower than those of a different batch. The result is that if the mechanism is designed and set to feed at a certain rate, although such rate may be satisfactory for one set of electrodes, it will be either too slow or too fast for a different set with the result that the arc is thrown out of adjustment and thrown out of focus if, for example, the device is used in connection with a searchlight or motion picture machine. It is obvious, however, that by varying the rate of rotation of the motor the rate of feed may be varied accordingly.

It is an object of my invention to provide means for varying the rate of rotation of the motor to the extent desired by providing a damping device through the medium of which the load of the armature of the motor is varied and make it possible to use in the arc lamp electrodes which are not uniform. It is also an object of my invention to provide other details of improvement tending to increase the efficiency and serviceability of an arc lamp of the above character.

To accomplish the foregoing and other useful ends my invention comprises means hereinafter more fully set forth, and claimed, reference being had to the accompanying drawing.

In Fig. 1 I show the device in elevation and partly in section; Fig. 2 is a top view of

the same device; Fig. 3 shows one form of the damping element of the lamp; Fig. 4 another form of the damping element, and Fig. 5 is a diagrammatic lay-out of the electrical circuits of the apparatus. 60

Referring more in detail to the accompanying drawings electrodes 1 and 2 are moved by the threads 3 and 4 respectively on the screw 5, which latter is in frictional engagement with the gear wheel 6. The gear wheel 6 is in engagement with the worm 7, the shaft 8 of which worm is supported by the bearings 9 and 10. To the shaft 8 there is secured another gear wheel 11 which latter is driven by the motor 12 through the medium of the worm 13 on the motor shaft. It will be observed that the lower portion of the screw 5 extends through the bearing 14 and is provided at its lower end with a head 15 which is rigidly secured to the screw 5 so that by turning the head the screw may be turned. In view of the frictional engagement between the screw 5 and the gear 6, as previously stated, the screw may be rotated irrespective of the gear 6 by turning the knob 15. This arrangement is a hand adjustment superimposed upon the motor feed for use in case of emergency. The engagement between the screw 5 and the gear wheel 6 is in the nature of a friction clutch. It will be observed that the shaft is tapered and the bore in the hub 6^a of the gear 6 is correspondingly tapered. The gear is kept in working engagement with the screw 5 by means of the spring 16 which is interposed between bearing 14 and the hub 6^a of the gear. The force of the spring tends normally to force the gear up and maintain it forced on the screw 5 with sufficient pressure to transmit the driving force necessary for operating the screw 5 by the motor 12. This general arrangement for driving electrodes by motor thus far described in connection with the detailed description of Fig. 1 is more or less old in 90 the art and alone does not constitute my invention. 100

I will now describe the damping arrangement through the medium of which the rate of feed may be varied to suit electrodes of different kinds. On the motor shaft 17 I provide a metal disk 18 rigid with the shaft. In proximity to this disk, I provide a magnet 19. This magnet may be made in the form of a horse shoe and the disk may be 110

arranged to rotate between the poles as clearly indicated in the drawing. As shown in Fig. 3, the magnet is pivoted so that it may be rotated about the axis 20. By moving the magnet 19 with respect to the axis of the disk, the damping action of the magnetic flux, on a disk, may be varied. For the purpose of varying the relation of the magnet to the disk an adjusting screw 21 may be provided. The damping magnet may be an electromagnet as indicated in Fig. 3, or it may be a permanent magnet, such as magnet 22, as indicated in Fig. 4. Furthermore, there may be a number of magnets acting upon the disk instead of only one. It will be observed that in Fig. 4 the permanent electromagnet is pivoted in an upright position and may be adjusted through the medium of the set screw 23. Furthermore, the damping structure may be a cylinder in place of the disk or a squirrel cage rotor in a suitable magnetic field which is adjustable with respect to the rotor as is well known in the field of induction motors.

Referring to Fig. 5 a suitable source of current such as a dynamo 25 is shown across the conductors 26 and 27. Across said conductors is placed the arc, the electrodes 3 and 4 of which are shown. In series with the arc there is provided a stabilizing resistance 28. Across the stabilizing resistance is the winding 29 of the electromagnet 19, Fig. 3. Across the source of current is connected the motor 12, the field 30 of which is shown in shunt with the armature. In series with the motor there is connected a resistance 31 in order to make the motor more sensitive in changes in load. With the arrangement shown the greater the current drawn through the arc the greater will be the energization of the electromagnet 19 and consequently the greater will be the load on the motor. Therefore with the circuit and arrangement indicated by Fig. 5 the system becomes substantially automatic after the first adjustment for if the current rises in the arc, due to the carbons approaching one another, the damping ac-

tion of the damping electromagnet becomes greater as it becomes more and more energized due to the rise in current through the arc. The result is, therefore, that the motor slows up giving the carbons more time to burn and thereby increase the length of the arc. When, however, the reverse is the case, as when the current in the arc has been reduced, due to too great a lengthening of the arc, then the damping magnet is automatically weakened and the speed of the electrode automatically accelerated. A condition of equilibrium therefore exists between these two conditions which will be maintained so that the arc will burn steadily with the electrodes at the proper working distance from each other.

What I claim as new and desire to secure by Letters Patent of the United States, is:

1. In an arc lamp an electrode feeding mechanism and an electric motor for operating said mechanism to continuously feed one of the electrodes, a magnet, and a metallic disk connected with the motor to be rotated thereby, said disk interposed in the magnetic circuit of said magnet, said disk and magnet serving as a magnetic brake for the motor, and means for varying the strength of the magnetic field of the magnet about said disk for varying the rate of feed of said electrode.

2. In combination with a source of current, an arc lamp, an electrode feeding mechanism, an electric motor for driving said mechanism and an electromagnet damper device for varying the speed of the motor and varying the rate of motion of the feeding mechanism, and resistance in series with said motor to increase the sensitivity of the motor to variations in load, and a resistance in series with the arc to stabilize the arc and a shunt circuit about said arc-stabilizing resistance, said shunt circuit for energizing said electromagnet damping device.

In witness whereof, I have hereunto set my hand this twenty-third day of July, 1923.

ELIHU THOMSON.
